UNITED STATES PATENT OFFICE.

GEORGE L. SMITH, OF RICHMOND, INDIANA, ASSIGNOR TO SWAYNE-ROBINSON & CO.,
OF RICHMOND, INDIANA, A CORPORATION OF INDIANA.

MOLDER'S FLASK.

Application filed May 25, 1927. Serial No. 193,998.

My invention relates to improvements in molders' flasks and is particularly directed towards that type of flask which is removed from the sand mold after the same has been formed.

It is one of the objects of my invention to provide a mold flask which will permit of speedy and accurate handling on the part of the molder, and particularly when removing the flask from the sand.

Another object of my invention is to provide an improved form of sand plate for the cope of the flask which may be easily and readily manipulated by the operator.

Another object of my invention is to provide improved means for guiding the cope relative to the drag during the separation of the same.

Other objects and advantages will appear more fully in the appended specification and claims.

In the embodiment of my invention illustrated in the accompanying drawings,

Fig. 1 is a side elevation, partly in section, 25 of a flask embodying my invention;

Fig. 2 is an end elevation thereof, partly in section;

Fig. 3 is a detail section showing more particularly the cope and match-plate guide;

Fig. 4 is a partial sectional view on the line 30 4, 4 of Fig. 2;

Fig. 5 is a partial horizontal sectional view showing more particularly the operating means for the sand rims;

Fig. 6 is a detail section showing the mounting of the sand rims, and

Fig. 7 is a transverse section of a modified form of guide pin.

In the embodiment illustrated the flask is 40 of the usual taper type and comprises the drag 1 and cope 2. At each end of the drag there is provided a handle 3 bolted or otherwise secured to the strengthening ribs 4 formed on the exterior of the drag. Also secured to the drag is a guide pin 5 which may be of any suitable configuration and is illustrated in the structures shown in Figs. 1 to 5 as being of triangular shape. This pin 5 is provided at its lower end with laterally extending flanges 6 arranged to be bolted to the ribs 4 by the same bolts which secure the handle 3 in position. These flanges, it will be noted, lie below the top edge of the drag although the pin 50 in its over-all length extends from a point

near the bottom of the drag to a point approximately at the top of the cope.

In some instances it is desirable to surround the bottom portion of the mold with a band and to this end for supporting this surrounding band 7 in position during the ramming of the sand in the drag, I provide inwardly extending fingers 8 on the top edge of the drag, which fingers project inwardly beyond the inner face of the drag. These fingers are preferably counter-sunk below the top edge of the drag so that the edge of the drag will present a straight surface and in use, when the drag is turned up-side down for the purpose of ramming the same, provide supports for the band 7 during the ramming operation. After the sand has been rammed the sand itself will support the band when it is turned right side up.

The cope 2 is provided at its bottom edge with an annular over-hanging skirt 9, the bottom edge of which rests upon the top edge of the drag and the lower portion of this skirt extends slightly below the sides 10 of the cope to provide a clearance between the lower edges of the sides and the top edge of the drag. 75 In this clearance is arranged a sand rim formed in four sections. This rim is formed of two side sections 11 and two end sections 12. Each of the sections comprises an angle member, the vertical portion 13 of which extends upwardly on the exterior of the side or end of the cope. The sections are hingedly mounted on the exterior of the cope by means of vertically extending ears 14, preferably lying between reinforcing ribs 15, through which and the ears pivot pins 16 are passed. The sections are biased inwardly by means of coiled springs 17 surrounding the pivot pins and having one end bearing on the top flange of the cope and the opposite end bearing on the ear. The two side sections are provided with rounded corners and their inner edges are provided with diagonally extending cam surfaces 18 adapted to overlap similar cam surfaces 19 on the two end sections. The two end sections are provided with operating handles 20 by means of which the sections may be rocked on their pivots and when so rocked outwardly the same surfaces 19, engaging the cam surfaces 18, will also rock the side sections outwardly so that the sand rim will be withdrawn to permit the cope to be raised clear of the mold.

The operating handles 20 for the sand rim lie below the handles 21 secured on the ends of the cope and these handles 21 have bolted thereto V shaped guides 23 adapted to cooperate with the pins 5 for guiding the cope as it is being raised from the drag. These guides extend downwardly from the handles 21 and are provided with bolting flanges 24 by which they may be secured to the handles 21. By extending the guides 23 downwardly to a point in line with the bottom edge of the cope, the guides engage the pins until the bottom edge of the cope clears the top of the pins so that a proper guidance of the cope is insured during its lifting movement.

In some instances it is desirable to use a match plate in connection with the flask and under such circumstances the match plate 25 is provided at its ends with guides 26 bolted thereto and extending downwardly therefrom. These guides engage the guide pins 5 in a manner similar to that of the guides 23. But it will be noted that due to the fact that the lower end of the pin extends downwardly so far that with the guide 26 extending downwardly from the match plate, there is ample clearance to accommodate the guide 23.

In Fig. 7 I have illustrated a modified form of guide pin. In this figure I provide a base plate 27 adapted to be bolted to the ribs 4 in the manner similar to that of the ears 6, and this base plate is provided with a half round recess 28 adapted to receive a round guide pin 29. This pin is provided with a bolt hole 30 counter-sunk on both sides of the pin, and the pin is secured in position by means of a suitable bolt or bolts passing therethrough, the heads fitting into the counter-sunk openings so as to leave the face of the pin clear. When one side of the pin becomes worn it is obvious that the pin may be removed and reversed.

In operation, after the cope has been placed upon the drag and the sand rammed in the cope, the cope may be lifted from the drag, with the sand therein held from dropping out by the sand rim, which is urged in its projected position by the coiled springs 17. After the pattern has been removed from the drag, or the match plate removed from position, the cope may be placed back on the drag and the operator lift the entire flask from the mold by grasping the handles 21 and 3 between the thumb and first two fingers beneath the handle 3 and manipulating the handle 20 to retract the sand rim and then lifting the entire structure clear of the mold.

In view of the fact that the fingers 8 project beyond the inner face of the drag, as the drag is lifted from the sand, these fingers would scrape across the edge of the mold and

tend to break it up. I therefore provide on the inner face of the cope immediately above the fingers 8, pattern ribs 31, which leave channels in the side of the sand to accommodate the fingers 8 as the flask is lifted. 65

I claim as my invention:

1. A molding flask section having side walls defining a mold space, a sand strip comprising a plurality of sections each hingedly mounted on said side walls and swingable on said hinges into and out of said space and having co-acting cam surfaces, and operating means connected to certain of said sections. 70

2. A molding flask section having side 75 walls defining a mold space, a sectioned sand strip hingedly mounted on said sand walls and swingable on said hinges into and out of said space, means for biasing said sections into said space, means on two of said sections 80 for retracting said sections from said space and means on the other two sections engaged by said first two sections for simultaneously retracting the other two sections.

3. A molding flask section having side 85 walls defining a molding space, said walls being provided at their bottom with an overhanging skirt, the bottom edge of which projects beyond the bottom edge of the section, a sand strip hingedly mounted on said side 90 walls and arranged within said skirt and swingable on said hinges into and out of said space.

4. A molding flask section having side walls defining a mold space, lifting handles 95 on two of said side walls, a sand strip hingedly mounted on said side walls and swingable on said hinges into and out of said space, biasing means for maintaining said strip in said space and manipulating handles for said sand strip beneath the lifting handles of the section. 100

5. A molding flask comprising a pair of sections, one of said sections having inwardly projecting sand supporting ears extending 105 beyond its inner face for supporting a mold band and the other section having substantially vertical rib patterns on its inner face in alignment with said ears.

6. A molding flask section having side 110 walls defining a mold space, a sand strip comprising a plurality of sections arranged beneath one edge of said walls, said sections having ears extending parallel with and pivoted to the outer face of the side walls of 115 the section and means for simultaneously operating said sections.

In witness whereof I, GEORGE L. SMITH, have hereunto set my hand at Richmond, Indiana, this 23rd day of May, A. D. one thousand nine hundred and twenty seven. 120

GEORGE L. SMITH.
